CLAIM

The ornamental design for a chisel tip for use with expandable broadheads, as shown and described.

DESCRIPTION

FIG. 1 is a front view of a two-bladed expandable broadhead having a shock collar and a three facet chisel tip as shown in FIGS. 5-10;

FIG. 2 is a perspective view of FIG. 1;

FIG. 3 is a front view of a two-bladed expandable broadhead having a shock collar and a four facet chisel tip as shown in FIGS. 11-16;

FIG. 4 is a perspective view of FIG. 3;

FIG. 5 is a side view of a three facet chisel tip showing the spiraling and concave nature of the chisel tip as shown in FIG. 1;

FIG. 6 is a cross section view taken along the line 6-6 as shown in FIG. 5;

FIG. 7 is a cross section view taken along the line 7-7 as shown in FIG. 5;

FIG. 8 is a cross section view taken along the line 8-8 as shown in FIG. 5;

FIG. 9 is a top view of the three facet chisel tip as shown in FIG. 5;

FIG. 10 is a perspective view of the three facet chisel tip as shown in FIG. 5;

FIG. 11 is a side view of a four facet chisel tip showing the spiraling and concave nature of the tip as shown in FIG. 3;

FIG. 12 is a cross section view taken along the line 12-12 as shown in FIG. 11;

FIG. 13 is a cross section view taken along the line 13-13 as shown in FIG. 11;

FIG. 14 is a cross section view taken along the line 14-14 as shown in FIG. 11;

FIG. 15 is a top view of the four facet chisel tip as shown in FIG. 11; and,

FIG. 16 is a perspective view of the four facet chisel tip as shown in FIG. 11.
